UNITED STATES PATENT OFFICE.

JOHN SMALLEY CAMPBELL, OF LONDON, ENGLAND.

DENTAL VULCANIZER.

SPECIFICATION forming part of Letters Patent No. 699,653, dated May 13, 1902.

Application filed June 8, 1901. Serial No. 63,750. (No model.)

To all whom it may concern:

Be it known that I, JOHN SMALLEY CAMPBELL, a citizen of the United States of America, residing at 11 Pall Mall, London, England, 5 have invented a new and useful Improvement in Dental Vulcanizers, of which the following is a specification.

Dental vulcanizers have heretofore been constructed with an opening at the front, giving admission to the vulcanizing-chamber for introducing or withdrawing the dental molds, such opening being closed by a door, making a steam-tight joint therewith. Such form of dental vulcanizer is shown and described in 15 the specification of my Letters Patent No. 217,728, dated July 22, 1879.

The object of my present invention is to improve the construction of vulcanizers of the class above mentioned, such improvement 20 consisting in certain means for supporting, closing, and opening the door to the vulcanizing-chamber, for supporting the entire apparatus, and for providing drainage for the condensed steam which is formed in the vul- 25 canizing-chamber.

In the accompanying two sheets of drawings, which form part of this specification, and in which similar letters of reference denote similar parts throughout, I show a mode 30 for applying my invention in practice.

Figure 1 is a sectional elevation of the entire apparatus through the line A A in Fig. 2, and Fig. 2 is a plan of the same. Fig. 3 is a plan, and Fig. 4 is a sectional elevation 35 through the line B B in Fig. 3, of the supporting-base detached from the upper part.

In Figs. 1 and 2, C is the vulcanizing-chamber, surrounded on the bottom and sides, with the exception of the opening C', by the steam-jacket D. The chamber, with its surrounding jacket, is preferably circular in plan, while the face of the opening C' is flat, as shown clearly in Fig. 2. At the center of the exterior of the top of the chamber is preferably 40 located a circular projection E and at the center under the bottom is a similar projection E'. These said projections constitute preferable forms of pivots, respectively, for two horizontal arms F F', which at their outer 45 ends are rigidly connected by a bar or yoke G. The arms F F', with their connecting bar or yoke, constitute a preferred form of door-

supporting member, which by reason of the location of its pivots works exclusively in a horizontal path of movement. The said yoke 55 G is drilled and tapped to receive a screw H, which has pivoted to its inner end the door J, which closes the opening C'. A collar on the end of the screw H and a plate J', formed in halves and fixed to the door, permit the said 60 screw to turn freely in the door and at the same time keep them securely connected. When it is desired to open the chamber, the screw H is turned till the door is drawn forward into the position shown in full lines in 65 Figs. 1 and 2, and the arms F F', yoke G, screw H, and door J can then be swung around into the position shown in dotted lines in Fig. 2, leaving the opening C' perfectly clear for the insertion or removal of the molds. To 70 close the chamber, the whole is swung back till the arm F' abuts against the stop K, the door being then exactly opposite the opening C', and the screw H is turned till the said door is securely fixed in place. The edge of 75 the door abuts against a soft-metal ring let into an annular groove around the opening, making a fluid-tight joint.

The supporting-base consists of a circular stand M, provided with feet and having three 80 sockets P P P, which receive the ends of the screw-studs L, provided to close openings in the jacket D for removing the core after it is cast in manufacturing. A sheet-metal casting R is affixed to the chamber and its sup- 85 porting-base, thus connecting them securely together. In the front part of the said base and preferably formed in one therewith is a tray N, which receives any condensed steam or water escaping from the chamber C when 90 the door is opened. Drainage from the said tray is provided by a pipe O, to the nozzle of which a hose may be attached, if desired.

The center of the projection E is drilled and tapped to receive a screw for applying the 95 necessary pressure to the molds, and the apparatus is supplied with a gage, thermometer, cocks, and other fittings usual in vulcanizers of this class, but which are not shown in the drawings, they being well understood and 100 not forming any part of the present invention.

The main advantages of my invention consist in the fact that the operator has never to handle the door, which necessarily becomes

highly heated in use. The said door can never be misplaced. It is opened and closed by merely turning a single screw and always comes accurately into the correct position for closing. The base forms not only a convenient support, but a means of drainage, and the whole apparatus is rendered very compact and self-contained.

Having now described my invention, what I claim, and desire to secure by Letters Patent, is—

1. In a vulcanizer the combination of a vulcanizing-chamber provided with an opening on one side thereof, a door-supporting member pivotally secured near its opposite ends to the vulcanizer and having a horizontal path of movement, a door carried by said member, and means for opening and closing the same, substantially for the purpose specified.

2. In a vulcanizer the combination of a vulcanizing-chamber provided with an opening on one side thereof, a door-supporting member having a horizontal path of movement, a door carried by said member, means for actuating the door, and means for limiting the movement of said door-supporting member when the door is in the correct position for closing, substantially for the purpose specified.

3. In a vulcanizer the combination of a vulcanizing-chamber provided with an opening on one side thereof, a door-supporting member having a horizontal path of movement, said member consisting of a pair of arms, one pivoted to the top and the other to the bottom of said chamber, and a yoke connecting said arms, a door carried by said yoke, means for actuating the door, and a stop for limiting the movement of the door-supporting member, substantially as and for the purpose specified.

4. In a vulcanizer the combination with a chamber provided with an opening on one side thereof, a door-supporting member having a horizontal path of movement, and consisting of a pair of arms, one pivoted to the

top and the other to the bottom of said chamber and a vertical yoke connecting said arms, a door carried by said yoke, and means for actuating said door.

5. In a vulcanizer the combination of a vulcanizing-chamber provided with an opening on one side thereof, a pair of arms and a vertical connecting-yoke constituting a door-supporting member, said arms being pivoted to the chamber one at the top and the other at the bottom thereof, at the central vertical axis of the vulcanizer, and a door and means for actuating it carried by the yoke.

6. In a dental vulcanizer the combination of a vulcanizing-chamber with opening at the side, a supporting-base, and a drainage-tray on said base, substantially as and for the purposes set forth.

7. In a dental vulcanizer the combination of a vulcanizing-chamber with opening at the side, a pivoted yoke carrying a door, a supporting-base with sockets, projections on said chamber engaging with said sockets, a drainage-tray and a duct leading from said tray, substantially as and for the purposes set forth.

8. In a dental vulcanizer the combination of a vulcanizing-chamber, an opening thereto at the side, an arm pivoted to the top of said chamber, an arm pivoted to the bottom of said chamber, a yoke connecting said arms, a screw in said yoke, a door carried by said screw, an abutment for said arms, a supporting-base, a casing connecting said chamber and said base, and a drainage-tray on said base, substantially as and for the purpose set forth.

In testimony that I claim the foregoing as my invention I have signed my name in presence of two subscribing witnesses.

JOHN SMALLY CAMPBELL.
